Inventor:

Philo H. Munson,

United States Patent Office.

PHILO H. MUNSON, OF FRANKLIN TOWNSHIP, ASSIGNOR TO HIMSELF AND
ELIAS BRECHT, OF STORRELOMIA, PENNSYLVANIA.

Letters Patent No. 67,565, dated August 6, 1867.

IMPROVED WASHING MACHINE.

The Schedule referred to in these Letters Patent and making part of the same.

TO ALL WHOM IT MAY CONCERN:

Be it known that I, PHILO H. MUNSON, of Franklin township, in the county of Erie, and State of Pennsylvania, (Edinboro Post Office,) have invented a new and useful improvement on Washing Machines; and I do hereby declare that the following is a full, clear, and exact description of the construction and operation of the same, reference being had to the annexed drawings, making a part of this specification, in which—

Figure 1 is a perspective view, and

Figure 2 a section through $x y$.

A, the main roller, fitted on the surface. B, the axle of this roller at the crank end. C, the axle or bearing at the opposite end. d e, connecting-rods, by which pressure is applied to the main roller. f g, bar connecting these rods, on the middle of which the lever $i' l$ presses. h', weight by which, as it moves towards $i' l$ or g' , the pressure on $g f$ and the bearings B C and roller A is increased or diminished. $i' l$, the lever, hinged at l, carrying h' , and pressing at g' the middle point of the bar $f g$. j, a bar running across the bottom of the wash-box, and fastened to it, for the purpose of furnishing guides for the connecting-rods d e. k, a bar fastened to the bottom of the box, in the middle of which is attached the hinge m. n o, four blocks fastened to the inside of the wash-box, to hold the roller-frame. p q, the frame for the small rollers. n and o and p q are not sectional views through $x y$, but perspective views as they appear on the side of the box represented in fig. 2. $r^1 r^2$, small rollers, with bearings at each end running in p q, the sides of the roller-frame; the main roller barely touches these rollers. S E', the connecting-rod and bearing on the opposite side of the box. So far this figure is not a section through $x y$. t v, metal bottom nailed securely to the sides and ends. Instead of the weight, springs may be used to press roller A down.

The operation is as follows: The box is filled with water above the rollers r^1 . When the motion of the main roller is from A' towards q the garment is thrust in at r^1 . The pressure and motion of roller A' carry it through over roller $r^1 r^2$. Before the garment passes entirely from roller r^1 the motion of the crank-end of roller A' is reversed, and as it moves from q towards A' the garment is carried between roller A' and rollers $r^1 r^2$. Before it has escaped from roller r^1 the motion is again reversed, and so on until the garment is washed.

Small garments are placed in a net-work sack, and are thus run through the machine together.

What I claim as my invention, and desire to secure by Letters Patent, is—

The arrangement of the small rollers r^1 with the crank-roller A, pressed down by the lever, weight, and their connections, all constructed and operated substantially as described.

PHILO H. MUNSON.
